FILM REEL FOR CINEMATOGRAPH APPARATUS

Leo Goldhammer and Ferdinand Stiefenhofer,
Munique, Germany, assignors to Agfa Ansco
Corporation, Binghamton, N. Y., a Corpora-
tion of New York

Application September 17, 1931, Serial No.
583,442, and in Germany September 29, 1930

3 Claims. (Cl. 242—70)

With cinematograph apparatuses methods are known of rotating the film take-up reel by means of friction gearing.

The present invention relates to friction gearing for this purpose. It differs from the friction gearing of known type in that the core of the reel is mounted in the interior of the hub of the film reel in such a manner that it grips frictionally.

One form of construction of the invention is illustrated in the annexed drawing, in which Fig. 1 is a front elevation of the film reel.

Fig. 2 is a section of the film reel along the line 2—2 of Fig. 1 on a larger scale.

The two flanges 1 of the film reel are connected together in known manner by the hub 2. According to our invention the film reel core 3—adapted to be arranged on the driving axle of a cinematograph apparatus and located in the interior of the hub—is mounted in such a manner that it grips frictionally the film reel. In the form of construction illustrated the connection is produced in the following manner: On the core 3, provided with a flange 4, a disc 5 is mounted on the end remote from the flange 4. The outer surfaces of the two parts, the flange 4 and the disc 5, are provided with a friction covering. This covering may be made of leather or the like. Between the flange 4 and the disc 5 there is arranged a spring 7, which presses both parts against the inner walls of the flanges of the reel. The square-shaped core 3 is driven positively by the driving axle of the cinematograph apparatus and transmits its movement by means of the friction surfaces 6 to the film reel. In spite of the fact that the core of the film reel is driven

positively, the tension exerted on the film band in the winding-up process is uniform, as the strength of the tension is determined by the uniform pressing force produced by the spring 7 between the friction surfaces 6 and the flange 1 of the film reel. When the winding operation comes to an end, i. e. when the diameter of the wound-up film band has become greater, slip takes place between the core of the film reel and the film reel.

What we claim is:

1. A film reel for cinematograph apparatus comprising two flanges and a hub holding together said flanges, in said hub a core, fastly connected to said core a flange, a disc in said hub on the core, and a pressure spring between said flange and said disc and pressing both elements against the flanges of the reel. 65

2. A film reel for cinematograph apparatus comprising two flanges and a hub holding together said flanges, in said hub a core, fastly connected to said core a flange, a disc in said hub on the core, a friction covering on the outer surface of said flange and said disc facing the flanges of the reel and a pressure spring between said flange and said disc. 75

3. A film reel for cinematograph apparatus comprising two flanges and a hub holding together said flanges, in said hub a core, fastly connected to said core a flange, a disc in said hub on the core, a leather covering on the outer surface of said flange and said disc facing the flanges of the reel and a pressure spring between said flange and said disc. 85
